UNITED STATES PATENT OFFICE.

LEO EDELMANN, OF CHICAGO, ILLINOIS, ASSIGNOR TO E. EDELMANN & CO., OF CHICAGO, ILLINOIS, A CORPORATION OF ILLINOIS.

LAMP-CASING RING.

Application filed October 20, 1925. Serial No. 63,785.

To all whom it may concern:

Be it known that I, LEO EDELMANN, a citizen of the United States, residing at Chicago, in the county of Cook and State of Illinois, have invented certain new and useful Improvements in Lamp-Casing Rings, of which the following is a specification.

This invention relates to lamp casing rings 10 and particularly to a ring adapted for use upon an automobile lamp casing to secure the lens or glass thereof in place.

An object of my invention is to provide a ring which can be simply and cheaply manufactured and which is of rigid and durable construction.

A further object resides in so constructing the ring that fastening means of the types now ordinarily used, can be employed.

Another object is to so construct the connecting ends of the split ring that fastening receiving portions are provided without the necessity of applying special brackets or extensions.

With these and other objects in view, which will be apparent from a consideration of the disclosure, my present invention includes certain novel features of construction and combinations of parts which will 30 now be set forth in connection with the drawing.

In the drawing:

Figure 1 is a view in side elevation of 35 a lamp of the drum type having my invention applied thereto.

Figure 2 illustrates a modified form of the ring applied to a different type of lamp casing.

Figure 3 is an enlarged fragmentary detail view to better show the connection of the ends of the ring.

Figure 4 is a longitudinal sectional view through the ends of the ring with the fastening removed, and

Figure 5 is a detail perspective view of one end of the ring.

My invention is adaptable for application with a split ring of any cross sectional form, and rings intended for use on different connections. In Figure 1 I have illustrated two rings 1 and 2, of substantially the same form and construction, applied upon a light casing 3 of the drum type. In this showing one of the rings serves as a glass or lens retaining ring and the second ring is

employed to give a symmetrical shape and appearance to the lamp casing. It is common practice to construct headlights and other lamp casings of the drum type, with the body portion enameled and the end ring 60 portions nickelized or otherwise given a contrasting finish and my invention is readily adapted to such construction.

With the disclosure in Figure 2, the ring 4 is applied to a lamp casing 5 of substantially parabolical form, and whereas the rings 1 and 2 will preferably be substantially U-shaped in cross section, the ring 4 is of substantially semi-circular form in cross section and it will be appreciated as 70 the description progresses that my invention is applicable to various types and forms of retaining rings used upon lamp casings and in various other connections.

As best shown in Figures 4 and 5, the 75 ends 6 and 7 of the ring are split or cut transversely as at 8 and 9 slightly in from their extremities, and the material of the ring is pressed outwardly as at 10 on the outer sides of these cuts and is bossed inwardly as at 11 on the inner sides to provide fastening receiving openings as generally indicated at 12 in Figure 5. By pressing out material at 10 and bossing in as at 11, I find that it is possible to form a substantially circular opening without materially restricting or changing the cross sectional form of the ring.

A clamp screw 13 having a clamp nut 14 thereon is fitted through these openings 12 90 with the head of the screw against the cut edge 8 and the clamp nut 14 against the edge 9 or the reverse, and it will be appreciated that various other forms of fastenings can be readily fitted and secured through these 95 openings to draw in and more or less rigidly connect the split ends of the ring.

While I have herein shown and described only certain specific embodiments, forms and uses of my improved retaining ring, it will be appreciated that changes and variations can be made to adapt the ring for particular conditions of use without departing from the spirit and scope of my invention. 100

I claim:

1. A split retaining ring having slits formed transversely therethrough adjacent its extremities and having the material at the ends beyond said slits pressed out to 110 provide aligned fastening receiving loops.

2. A split retaining ring cut through transversely in its middle portion adjacent its extremities, and having the material thereof on the outer sides of the cuts bent 5 out and on the inner sides bossed in to provide fastening receiving openings.
3. A retaining ring of split ring form having slits formed transversely through the body thereof adjacent its extremities and 10 having the material on the outer sides of the slits pressed out and on the inner sides bossed in to form alined openings, a clamp screw fitted through the alined openings with its head bearing against the slit edge of the loop portion of one end of the ring, 15 and a clamp nut on said screw bearing against the similar edge on the remaining end of the ring.

In testimony whereof I affix my signature.

LEO EDELMANN.
